UNITED STATES PATENT OFFICE.

WM. W. PURDY, OF LIVERPOOL, OHIO.

ROLLING AND PRESSING WOOL.

Specification of Letters Patent No. 22,673, dated January 18, 1859.

To all whom it may concern:

Be it known that I, WILLIAM W. PURDY, of Liverpool, in the county of Medina and State of Ohio, have invented a new and Improved Mode of Rolling and Pressing Fleeces of Wool for Tying or Binding; and I hereby declare that the following is a full and exact description thereof, reference being had to the accompanying drawings and to the letters of reference marked thereon.

The nature of my invention consists, in providing the folding table "on which the wool is spread," with straps of leather, or "cord," which work in combination with a breast-piece, said straps being sufficiently long to extend the entire length of the table under the wool and back over the top of it, motion being given to the straps in the direction of the breast-piece by means of a roller. The wool is rolled up by the motion of the strap. The straps are attached to said roller at one end. The other end is attached to the end of the table. Said roller is made in two, or more, sections, and the straps are attached to the several sections of roller, by means of hooks. The sections of the roller may be worked independently of each other, and they are provided with pins or "catches" so that they may be connected together and form one roller. Each section of the roller is provided with a hand-wheel, also with a ratchet-wheel and dog so that each section can be worked by itself, the wool being rolled up to a certain point by the entire roller. Now should any part of the wool require more pressure, it can be given to it by uncoupling the section of roller in the vicinity of the part to be operated on, and drawing that part of the strap connected thereto tighter. By this means the whole roll of wool can be perfectly pressed with great facility.

To enable others skilled in the art to make and use my invention, I will proceed to describe its construction and operation, Figure 1, being an end view; Fig. 2, being a vertical view; Fig. 3, being a side view; Fig. 4, a detached portion of the roller, and journal of the section roller; Fig. 5, a section roller detached from the main roller; Fig. 6, an end view of a detached breast piece.

A, Figs. 1 and 3 is a piece of board which forms the body of the table, to which I fasten two cross-pieces, marked "B," Figs.

1, 2, and 3. Near the end of these cross-pieces I place the four legs which support the machine, as shown at C, Figs. 1, and 3. On each side of the piece A, is hinged two other pieces, marked D, which form the leaves, as seen at Figs. 1, 2, and 3. Said leaves are thrown up during the rolling and pressing of the wool for the purpose of keeping it in place, and retained in their position by means of the pins at T', as seen in Fig. 3. At the end of the table, and secured to the body board, is a piece of wood with its side facing the table curved out, and having its upper edge made sharp, as shown in the detached section Fig. 6, also shown at E, Figs. 1, 2, and 3. To the bottom of this piece E, is secured four straps marked F, Figs. 2, and 3. These straps after they are brought over the upper edge of the breast piece E are secured to the roller as seen at G, Fig. 3, by means of the hooks H, shown on the rollers I, and I', Figs. 1, and 2. I' shown in Figs. 1 and 2 is an outside case that is made loose on the journal of the main roller. Said journal is marked J, Fig. 4. The case or "section roller" Fig. 5, when placed on the journal J, Fig. 4, may be prevented from turning independently of the roller I, by putting a pin through the holes K, Figs. 4, and 5, it being necessary to connect them when the wool is being rolled up. The roller is operated by means of the crank L, Figs. 1, 2, and 3, and when the roller is brought to a certain point of pressure, it is kept in place by means of the ratchet M, and dogs, N, as shown in Figs. 1, 2, and 3.

P is a hand wheel by which the section roller is operated.

R, and R' are supports that connect the roller to the table.

S Fig. 3, is a roll of wool, rolled up "for pressing" by the straps F, the straps being kept in contact with the sharp edge of the breast piece as seen at S', Fig. 3. This is to prevent the wool from being drawn over onto the roller, by the straps.

T, Figs. 2, and 3, is a strip of wood, that extends across the under part of the table, for holding the pins T'. These pins extend about half way up the leaves of the table, when said leaves are in a vertical position, the said piece T being attached to the table by means of the hinges, marked V, in Fig. 3. These pins can be dropped down by

pressing on the lever U, when the leaves of the table require to be dropped to receive another fleece.

What I claim as new and desire to secure by Letters Patent is--

The combination of the sectional rollers I, and I', with the straps F, and breast-piece

E for the purpose of rolling, and pressing fleeces of wool as herein described.

WILLIAM W. PURDY.
